UNITED STATES PATENT OFFICE

JOSEPH ANDERSON, OF PITTSBURG, PENNSYLVANIA.

GAS-FURNACE FOR MELTING GLASS, &c.

SPECIFICATION forming part of Letters Patent No. 307,829, dated November 11, 1884.

Application filed August 28, 1884. (No model.)

To all whom it may concern:

Be it known that I, JOSEPH ANDERSON, of Pittsburgh, in the county of Allegheny and State of Pennsylvania, have invented a new and useful Improvement in Gas-Furnaces for Melting Glass, &c.; and I do hereby declare the following to be a full, clear, and exact description thereof.

My invention relates particularly to the construction of glass-melting furnaces designed for use with gas, and more particularly natural gas; and it consists of certain improvements on the construction shown in my application, No. 137,395, filed July 11, 1884.

The natural gas being supplied by means of mains and service or distributing pipes to the various works and places of use, it is often necessary for the gas companies to turn off the gas in order to make the attachments or 15 pairs, and the gas is frequently turned off for a sufficient length of time to chill the glass in the pots, so that not only is the melt or batch lost, but the furnace is practically destroyed, as it is necessary to take it down to remove the 20 pots. Consequently it becomes a very serious difficulty in the use of gas for such purposes.

My invention is designed, among other things, to obviate this danger and to provide means for sustaining the temperature of the 25 furnace in case the gas is turned off.

To enable others skilled in the art to make and use my invention, I will now describe it by reference to the accompanying drawings, in which—

Figure 1 is a vertical sectional view of a 30 glass-melting furnace, showing my improvement. Fig. 2 is a detached view of the gas pipes and burner. Fig. 3 is a sectional view on the line $x-x$ of Fig. 1.

Like letters of reference indicate like parts in each.

The furnace shown in the drawings is the ordinary form of a pot-furnace for melting glass, and the pipes shown in Fig. 1 are divided on the line $y-y$ of Fig. 2. The furnace has the usual bench, a , for supporting the pots b , eye c , crown d , work-holes e , and flues f . Below the bench a is an air-chamber, g , having closed sides and a door or man-hole, g' . Above the crown d of the furnace is a ring or coil of pipe, k , having an open end, k' , for the

admission of air, and a valve, k^3 , for regulating its supply to the chamber g , so as to proportion it to the amount of gas admitted thereto. The pipe k extends down the side of the 55 furnace, either outside of the wall, as shown at k^2 , or through the wall, if desired, to the side of the chamber g , which it enters through the wall g^2 . The pipe k is designed to effect the heating of the air which is supplied to the 60 chamber g , to support the combustion of the gas or other fuel therein. The air entering at the open end k' is drawn through the coil k , and thence through the vertical pipe k^2 , into the chamber g by the influence of the draft of 65 the stack h . The gas is supplied to the furnace by means of the pipes i , which extend through the walls g^2 of the chamber g , and are connected by suitable fittings with the gas-main i^2 . The flow of the gas is regulated by 70 means of the valves i' . The burner l is composed of two semicircular pipes, l' , forming a ring of larger diameter than that of the eye c , so as to be under the protection of the bench a , in order that in case of the breaking of a 75 pot in the furnace the molten glass flowing down through the eye shall not come in contact with the burner and clog up its perforations. The burner is perforated on its inner upper side, so that the jets of gas shall be projected toward the eye c . Each semicircle of the pipes which form the burner is connected to one of the pipes i , in which is a union, i' , so that if either of the semicircles l' becomes 80 clogged up or needs repairs it can be taken 85 out by detaching the pipe connected to it at the union i' . By this arrangement it is possible to remove one half of the burner without interrupting the operation of the other half, so that an accident to one portion will 90 not endanger the furnace, as the heat can be sustained by the use of the remaining half.

Entering the horizontal pipes i at the fittings n are smaller pipes m' , which are connected to a supply-pipe, m , and which are provided with valves m^2 . The pipe m is designed to supply benzine or other suitable light hydrocarbon; or it may be connected with a gas-holder or other reservoir of gas so as to be independent of the main i^2 for its supply. This 95 provision is made so that in case the gas-supply from the pipe i^2 is turned off the fuel, gas- 100

eous or liquid, necessary for maintaining the heat of the furnace may be supplied from the pipe m , which can be accomplished merely by opening the valves m' and allowing the gas or liquid fuel to flow therefrom to the burner through the pipes i . In this manner I am enabled to obviate all danger to the furnace arising from the stoppage of gas from the main i' .

My improvement is of great value in a glass-melting or similar furnace where any interruption of the heat is attended with serious and detrimental results. It is simple and cheap in construction, easily operated, and frees the furnace from absolute dependence upon one fuel-supply.

I do not limit myself to the use of my improvement in glass furnaces, but claim it also in connection with other furnaces, especially those in which it is desirable to maintain a given temperature in the furnace.

What I claim as my invention, and desire to secure by Letters Patent, is—

1. The combination of a furnace gas-burner and its gas-supply pipe or pipes with second-

ary supply-pipes communicating therewith 25 and having suitable valves, whereby the burner can be supplied with fuel from said secondary supply-pipes, in case of the interruption of supply through its ordinary pipes, substantially as and for the purposes described.

2. A burner for heating purposes, composed of two semicircular sections, each connected to a separate pipe for supplying gaseous or liquid fuel thereto, and together forming a circular burner, substantially as and for the purposes 35 described.

3. A burner for heating purposes, composed of two separate sections, each connected to a separate pipe for supplying gaseous or liquid fuel thereto, substantially as and for the purposes described.

In testimony whereof I have hereunto set my hand this 25th day of August, A. D. 1884.

JOSEPH ANDERSON.
